Marquez IP Law Office, PLLC(57) **CLAIM**

The ornamental design for a foldable lightweight solar panel, as shown and described.

DESCRIPTION

FIG. 1 is a perspective view of a foldable lightweight solar panel, showing the new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a front view thereof in an open configuration;

FIG. 9 is a rear view thereof in an open configuration; and,

FIG. 10 is a perspective view thereof in an open configuration.
